[57] CLAIM

The ornamental design for a watercraft, as shown and described.

DESCRIPTION

FIG. 1 is a top perspective view of a watercraft showing my new design;

FIG. 2 is a top plan view thereof;

FIG. 3 is a side elevational view thereof, the opposite side view being a mirror image of that shown;

FIG. 4 is a bottom plan view thereof;

FIG. 5 is a rear elevational view thereof;

FIG. 6 is a front elevational view thereof;

FIG. 7 is a top perspective view of a second embodiment of the watercraft;

FIG. 8 is a side elevational view of FIG. 7, the opposite side view being a mirror image of that shown;

FIG. 9 is a top plan view of FIG. 7; and

FIG. 10 is a bottom plan view of FIG. 7.
